INVENTOR
Edwin H. Gibb,

BY C. P. Goepel

ATTORNEY

UNITED STATES PATENT OFFICE.

EDWIN H. GIBB, OF NUTLEY, NEW JERSEY, ASSIGNOR TO GIBB YIELD SLIDE CORPORATION, OF NEW YORK, N. Y., A CORPORATION OF NEW YORK.

COMPUTING DEVICE.

1,413,021.

Specification of Letters Patent. Patented Apr. 18, 1922.

Application filed May 27, 1921. Serial No. 473,140.

To all whom it may concern:

Be it known that I, EDWIN H. GIBB, a citizen of the United States, and resident of Nutley, county of Essex, and State of New Jersey, have invented certain new and useful Improvements in Computing Devices, of which the following is a specification.

This invention relates to computing devices and has for its primary object to provide a simple and inexpensive device whereby the interest yield of stocks and bonds for different terms of years may be easily and quickly computed.

More particularly, the present invention contemplates the provision of a computing device of the above character in the form of a slide rule in which a movable web is mounted having indicia printed on its surface and a sheet of transparent material covering an exposed portion of the web, means for operating said movable web and a transparent slide member having interest or dividend rates marked thereon and provided within an index, the body of the device along each of its longitudinal edges having the purchase price of stocks and bonds respectively indicated thereon, in alignment with which the index on the slide is adapted to be positioned, the indicia upon said web denoting the interest yield for a term of years at the interest or dividend rate indicated upon the slide.

With the above and other objects in view the invention consists in an improved computing device and in the form, construction and arrangement of its several parts, as will be hereinafter more fully described, illustrated in the accompanying drawing and subsequently incorporated in the subject joined claims.

In the drawing wherein I have disclosed one practical construction of the device, and in which similar reference characters designate corresponding parts throughout the several views:

Figure 1 is a plan view of the computing device;

Figure 2 is a transverse section taken on the line 2-2 of Figure 1;

Figure 3 is a fragmentary horizontal section showing the operating means for the web carrying rods, and

Figure 4 is a detail perspective view of the adjustable slide.

Referring in detail to the drawing, 5

designates the body of the device, preferably, though not necessarily, of wood and in the form of a flat bar of the requisite width and length, one longitudinal side of said bar being preferably chamfered or obliquely inclined as at 5'. The bar 5 is formed with the spaced parallel longitudinally extending cylindrical bores 6, which are connected with each other at their upper sides by the recess or channel 7 formed in the upper surface 60 of the bar and extending substantially for the full length thereof. To the marginal portions of this upper surface of the bar and at each side of the recess 7, strips of celluloid or other suitable material indicated at 8 70 are suitably secured, said celluloid strips bearing the spaced numbers A and B which respectively indicate the purchase price of stocks and bonds. A thin sheet of glass or other transparent material 9 extends over 75 the recess 7 and also preferably upon the strips 8 to prevent possible obliteration of the printed numerals upon said strips.

A longitudinally extending rotatable rod 10 is axially centered in each of the bores 6. 80 To these spaced rods the ends of the web 11 are respectively secured, said web extending through the recess or channel 7 beneath the transparent plate 9. The surface of the web is divided by longitudinally extending parallel lines and in the longitudinal divisions of the web surface the spaced numbers C are printed to indicate the interest yield of stocks or bonds at the different purchase prices. These numbers are arranged in 90 groups, each consisting of five longitudinal rows on the surface of the web, each group of numbers being associated with a year number indicated at D, which is printed upon the central portion of the web. 95

To one end of each of the rods 10 a pinion 13 is fixed, said pinions meshing with opposite sides of an operating gear 14 which is mounted upon the inner side of a cap 15 secured upon one end of the body bar 5 and closing the ends of the bores 6. The gear 14 may be conveniently operated by a suitable finger piece 16 fixed to the gear axis.

Upon the body 5 a slide member 17 is 105 longitudinally movable. This slide member is likewise formed of transparent material and has its ends inwardly flanged to engage with the beveled guide surfaces 18 formed upon the opposite side edges of 110

the body bar 5. On this slide an index line 17' is suitably delineated and at one side of said line, the characters E are printed or marked upon the surface of the 5 slide and are indicative of the interest or dividend rates of the stocks or bonds, said characters being spaced apart to correspond with the spacing of the rows of numbers C on the web.

10 From the foregoing description, the construction, manner of use and several advantages of the invention will be readily understood. Thus, assuming that it is desired to ascertain the interest yield of a bond maturing 15 in one year having an interest rate of 6% and purchased at 98½, the slide member is shifted upon the bar until the index line 17' thereof is in line with the number 98½ of the row of numbers B. The 20 dividend rate being 6%, the reading is taken at the point where the 6% rate on the slide coincides with the row of numbers C on the web and it is found that the interest yield is 7½%. If it is desired to compute the yield 25 for a bond of longer maturity, this may be readily done by rotating the gear 14 in the proper direction to move the web 11 and expose another group of the numbers C corresponding with the number of years to 30 maturity. In the same manner, the interest yield of stocks may be ascertained. Thus, if a certain stock is purchased at 124 and the interest rate is 7%, the web is first moved to indicate zero years and by then shifting the 35 slide member until the index line coincides with number 124 in the row of numbers A, the interest yield may be read upon the surface of the web.

It will be understood that the web 11 may 40 be of any desired length within reasonable limits and that the length of the bar 5 may be increased if desired so that the rows of numbers A and B can be extended to denote a greater range of prices. The device 45 as herein described is likewise susceptible of many other modifications in the form, proportion and arrangement of the several parts and I accordingly reserve the privilege of adopting all such legitimate changes as may 50 be fairly embodied within the spirit and scope of the invention as claimed.

I claim:

1. A computing device of the character described comprising a body bar having 55 parallel longitudinally extending bores and a recess in its upper surface communicating with said bores, rotatable rods axially cen-

tered in said bores, a web connected at its ends to said rods and extending through said recess, said bar having indicia upon its upper surface at each side of the recess, a transparent plate extending over said recess, said web having indicia thereon visible through said transparent plate, a transparent slide member longitudinally movable upon the 60 bar having an index thereon adapted to be positioned with respect to the indicia at each side of the recess and also bearing indicia adapted to be read in conjunction with the indicia on the web, and means for rotating 65 said rods to position the indicia on the web in said recess.

2. A computing device of the character described comprising a body bar having spaced longitudinally extending bores 75 therein and a recess in the upper side of said bar communicating with said bores, indicia on the upper surface of the bar at each side of the recess indicative of the purchase price of stocks and bonds respectively, said web 80 bearing indicia indicating the interest yield of stocks and bonds, and the term for which they are issued, a transparent slide member longitudinally movable upon said bar and extending over said recess, said slide member 85 having indicia indicating the interest or dividend rates of stocks and bonds and being provided with an index adapted to be positioned with respect to the purchase price indications at opposite sides of the recess, 90 and means for rotating said rods to move said web and position the indicia thereon in said recess.

3. A computing device of the character described comprising a body member having 95 a longitudinally extending slot and having indicia at the side of the slot, a web mounted for movement across the slot and having indicia thereon, and a slide movable longitudinally upon the body member and 100 adapted to register with any desired element of the indicia at the side of the slot, said slide having indicia thereon adapted to be read in conjunction with the indicia on the web, and said indicia at the above mentioned 105 parts being arranged to indicate the purchase price of securities, the interest or dividend rates of such securities and the interest yield of the securities at their purchase prices.

In testimony that I claim the foregoing as my invention, I have signed my name hereunder.

EDWIN H. GIBB.
